UNITED STATES PATENT OFFICE.

ABEL KLUGE AND ENEVAL KLUGE, OF ST. PAUL, MINNESOTA, ASSIGNEES, BY MESNE ASSIGNMENTS, TO BRANDTJEN & KLUGE INCORPORATED, OF ST. PAUL, MINNESOTA, A CORPORATION OF MINNESOTA.

PNEUMATIC FEEDING DEVICE FOR PRINTING PRESSES.

Application filed July 19, 1919. Serial No. 311,992.

To all whom it may concern:

Be it known that we, ABEL KLUGE and ENEVAL KLUGE, citizens of the United States, respectively residing at St. Paul, in the county of Ramsey and State of Minnesota, have invented a new and useful Pneumatic Feeding Device for Printing Presses, of which the following is a specification.

Our invention relates to improvements in pneumatic feeding devices for use more especially with printing presses of the platen type.

Its object is to provide a simple and durable device of this kind designed to grip a sheet of paper, remove it from a feeding table without disturbing adjacent sheets, place said sheet in position upon the platen of a press and after the impression is made to grip the printed sheet, carry it to a delivery table and release the same thereon, the gripping of the sheet by both feeding and delivery mechanisms being accomplished by means of suction, thus eliminating entirely the use of mechanical gripping appliances.

A further object is to provide a device of this kind adapted to be readily attached to printing presses of standard design.

A further object is to provide in a device of this nature, novel means for successively carrying sheets of paper to position within reach of the feeding arm and also to incorporate in said means, novel mechanism whereby the feeding table may be expeditiously replenished with additional sheets of paper.

Another object is to supply an improved attachment for platen presses whereby certain parts thereof may be readily adjusted to permit easy access to the platen and other parts of the printing press.

A further object is to supply in a device of this nature, novel means for actuating the tripping mechanism of a printing press whereby registration between the platen and bed of the press is prevented in case the feeding arm fails to grasp a sheet of paper from the feeding table.

The invention also comprises various novel structural features, mechanisms and combinations of parts, all of which will be herein-after described and claimed.

In the drawings, Fig. 1 is a (right) side elevation of a printing press of the platen

type with our improved feeding device attached thereto; Fig. 2 is a front elevation of the same; Fig. 3 is a (left) side elevation thereof; Fig. 4 is a view illustrating in detail the delivery arm and mechanism for operating the same; Fig. 5 is an enlarged sectional view taken on the line 5—5 of Fig. 2 and shows in detail the valve for opening and closing the air conduit leading to the suction grips on said delivery arm; Fig. 6 is a detail view illustrating in plan, the feeding table of our improved device and also shows in dotted lines the inoperative position into which said feeding table may swing; Fig. 7 is a detail sectional view taken on the line 7—7 of Fig. 6; Fig. 8 is a detail sectional view taken on the line 8—8 of Fig. 6; Fig. 9 is a detail view in elevation illustrating a ratchet device and thread gripping members which comprise part of the mechanism for advancing sheets of paper upon the feeding table; Fig. 10 is similar view and shows the cams for operating said thread gripping members; Fig. 11 is an enlarged sectional view taken on the line 11—11 of Fig. 6; Fig. 12 is a detail view illustrating the feeding arm and support therefor, the latter being shown in cross section to disclose a cut-off valve therein contained and also a piston for operating the press tripping mechanism; Fig. 13 is an enlarged sectional view in detail illustrating the feeding arm and bearing therefor, together with ports and air conduits forming the air passage way to the suction grips at the end of said arm; Fig. 14 is a detail sectional view taken on the line 14—14 of Fig. 12; Fig. 15 is a detail sectional view taken on the line 15—15 of Fig. 12 and illustrates a yielding finger for holding sheets of paper in position against feeding guides upon the platen of a printing press; Fig. 16 is a detail sectional view taken on the line 16—16 of Fig. 12; Fig. 17 is an enlarged sectional view taken on the line 17—17 of Fig. 12 and illustrates in detail a relief valve employed in the conduit communicating with the suction grips; Fig. 18 is a side elevation in detail showing the cams and lever assembly for operating the feeding and delivery arms; Fig. 19 is a side elevation in detail of the cam which actuates the cut-off valve shown in Fig. 14, and Figs. 20 to 29 inclusive are diagrammatic representations of the various parts of the device.

tations illustrating various positions of the feeding and delivery arms, together with the actuating cams therefor in various relative positions throughout one cycle of the latter.

5 In the drawings we have illustrated a platen printing press of usual construction comprising a frame 30, a bed 31 pivoted thereto, a platen 32, driving gear 33 connected with said bed and platen and hand-
10 lever 34 adapted to prevent engagement of the bed with the platen.

The embodiment chosen, as illustrative of our invention, comprises generally the following:

15 A feeding table 35 carried on the frame 30 of the press, a delivery table 36 mounted on said frame, an oscillatory feeding arm 37 suspended above the printing press and adapted to swing between said feeding ta-
20 ble and the platen of the press, and oscillating delivery arm 38 arranged to swing backward and forward between said delivery table and platen, a suction and pressure pump 39, the intake side thereof being con-
25 nected with suction grips 40 and 40^a upon said feeding arm and a suction grip 41 on the delivery arm, means for moving the feeding and delivery arms, means for ob-
30 structing and clearing the air conduits be-
tween said pump and grips, mechanism for advancing sheets of paper upon the feeding table 35 and an air jet 42 connected with the exhaust side of said pump to aid in sepa-
35 rating sheets of paper upon said table.

35 A sub-frame 43 attached to the main frame 30 of the printing press furnishes a mounting for the pump 39, the actuating mechanism for the feeding and delivery arms 37 and 38 and also for the standard arms 44 upon which said feeding arm 37 is sup-
40 ported, all of which will more fully hereinafter appear. Attached to the standard 44 and to the frame 30 of the printing press is a guard 45 for the driving gear 33 of the press. This guard has a post 46 extending upwardly therefrom and pivoted hori-
45 zontally upon the top of said post is a sup-
porting bar 47, said bar being turned down-
ward at the free end thereof to form a leg
50 48 which rests upon the delivery table 36. The feeding table 35, carried upon said supporting bar 47, is inclined upward from the front of the press. Sheets of paper placed edgewise upon said table are support-
55 ed in inclined position by a carrier 49, which is slidably mounted at its lower cor-
ners in ways 50 at the ends of said table. We provide mechanism for moving this carrier, step by step, to advance sheets upon
60 the feeding table, said mechanism being adapted also to permit free backward and forward movement of said carrier, whereby additional sheets may be readily put in place upon the table and the pack quickly and easily advanced to feeding position. This mecha-

nism includes, a screw 51 rigidly secured at one end to the center of the carrier 49. Said screw passes through a journal box 52 carried upon supports 53 secured to the feeding platform 35. A sleeve 54 revoluble in said journal box 52 slidably receives the screw 51. This sleeve 54 is enlarged at its forward end to form a disc or driven ratchet member 55, angular notches 56 being cut in the periphery thereof to provide seats for roller-dogs 57. Surrounding said disc 55 is a cup-shaped driving ratchet member 58 the inner periphery of the rim 59 contacting with the roller dogs 57. Upon clockwise rotation of said driving ratchet mem-
65 ber 58 (Fig. 9) said dogs are wedged be-
tween the periphery of said rim 59 and the inclined seats 60 of the notches 56 in said disc thereby imparting the motion of the driving ratchet member 58 to the driven ratchet member 55. During reverse or counter-clockwise movement of said driving clutch member, the dogs 57 cease to function and permit said driving member to turn freely. Slidably seated in depressions 61 in the face of the disc 55 are female screw members 62, each member being supplied with a pin 63 protruding therefrom. A fragmentary bushing 64 integral with said disc 55 forms a journal for a cover 65 and a collar 66 secured to said bushing holds said cover in place. The pins 63 on said female screw members rest in cam slides 67 in said cover, which operate upon counter-clock-
70 wise rotation to engage the members 62 with the screw 51 and to release said members from said screw, when the cover is turned in the reverse or clockwise direction. A grooved collar 68, attached to the sleeve 54 at the rear of the journal box 52, is supplied with a frictional brake band 69 adapted to yieldingly hold the driven ratchet member 55. A bell crank 70 is mounted upon the post 46 above the supporting bar 47. An actuating rod 71, removably attached to a pin 72 on one arm of the crank, oscillates said crank, while a second rod 73 having an adjustable and pivotal attachment at one end with said crank and a pivotal connection at its other end with the driving ratchet member 58, causes the oscillation of said driving member. The adjustable connection between the rod 73 and bell crank 70 is formed as follows: A radial slot 74 (Fig. 11) in the crank receives the reduced end of a pin 75, which passes through a washer 76 above the slot and is threaded in a nut 77 beneath the slot. This pin may be clamped in any position desired throughout the length of said slot. The rod 73 has an enlarged end with a bore therein to receive the pin 75, said end being furnished with a pointer 78 carried above a graduated scale 79 on the margin of said bell crank. This scale is graduated in accordance with va-
80

115
120
125
130

rious paper stocks, and with reference thereto accurate adjustment of the pin 75 is possible, and the desired advancement of the carrier 49 upon each oscillation of the driving ratchet member 58 is readily obtained. From the foregoing, it will be seen that when the cover 65 is turned to the extremity of its counter-clockwise movement, the screw is engaged by the female members 62 and upon each oscillation of the bell crank 70 the carrier is advanced a step, the length of which is determined by the adjustment of the pin 75 in said crank. Further it will be seen that in turning the cover, by hand, in a counter-clockwise direction, the carrier will be moved forward or backward through the action of the screw 51. This result is desirable when adjustment of the carrier through short distances is required. When it is desired, however, to quickly shift the carrier through greater distances, as is often necessary in replenishing the supply of paper and also in the initial adjustment of the carrier, the cover 65 is turned to the extremity of its clockwise movement thus disengaging the female screw members 62 from the screw 51 and permitting free backward and forward movement of the carrier 49. Reverse movement of the cover 65 engages the members 62 with the screw 51 and the movement of the carrier is again made dependent upon the rotation of the driven ratchet 55. The supporting bar 47 being pivoted upon the post 46 permits the swinging of the feeding table into inoperative position, as shown in dotted lines in Fig. 6, the rod 71 being necessarily first detached from the pin 72 on the bell crank 70. This position of the feeding table permits easy access to the platen and bed of the printing press. For the purpose of separating sheets of paper upon the feeding table, the rear margin of said table is serrated and beneath said margin the air jet 42 is mounted. Said jet comprises a pipe 80 having a number of openings 81 therein registering with serrations 82 in said table. Said pipe is connected through a tube 83 with the exhaust side of the pump 39, air being directed upward through said openings and between the first few sheets to be fed. Slidably mounted upon said pipe 80 are front guides 84. Each guide consists of a strip of sheet metal split longitudinally at one end thereof, one portion being turned substantially around the pipe 80, but not obstructing the openings 81 therein, while the other portion is turned back beneath the pipe and upward against the bottom of the feeding table 35 to form a sliding brace for said guide.

The delivery table 36 is secured in horizontal position upon the frame 30 of the printing press beneath the feeding table 35. The hollow standard 44 is secured to the sub-frame 43 and extends from a point near the floor to a point above the printing press. A bearing 85 mounted at the upper end of said standard consists of offset cylindrical housings 86 and 87 cast integrally and at right angles with respect to each other, communication between the two being obtained through an opening 88. The housing 86 closed at its upper end and threaded at its lower end upon said standard holds the housing 87 horizontally over the printing press. Within the housing 87 is an oscillatory cylinder 89 hereinafter, at times referred to as an eccentric. Said cylinder has a reduced extension 90 at the inner end thereof offset from the axis of said cylinder and an enlargement in the form of a disc 91 upon the opposite end thereof. A bore 92 passing longitudinally through said cylinder 89 extension 90 and disc 91 communicates through a port 93 in said cylinder with the opening 88 between the housings 86 and 87. An oscillatory, hollow shaft 94 having a port 95 registering with said port 93 is journaled in the bore 92 of said cylinder, the outer end of the shaft 94 being closed and supplied with an actuating arm 96 while the inner end of said shaft communicates with and carries the hollow-feeding arm 37. At the lower extremity of the feeding arm 37 is a cross-rod 97, having a bore 98 therein which communicates with the passageway 37^a in said feeding arm and upon this cross-rod a plurality of suction grips 40 and 40^a are mounted. The grips 40 are stationary and the grips 40^a are adjustable to suit sheets of paper of varying widths. Each stationary grip 40 (Fig. 6) includes a bearing 99 encompassing the cross-rod 97 and a conduit 100 depending therefrom having an enlargement at its extremity to form a suction cup or nozzle 101. The grip 40 is fixed upon said cross-rod with the conduit 100 therein in registration with a port 102 communicating with the bore 98 in said rod. Each slidable grip 40^a (Fig. 15) includes a clamp 103 encircling the cross-rod 97 and a conduit 104 having a cup or nozzle 105 similar to those of the stationary grips. Said conduit 104 is connected by means of a flexible tube 106 through a cutoff valve 107 with the passageway 37^a in the feeding arm 37. Said passageway is normally closed, at the upper end of said feeding arm by a ball-valve 108 which is yieldingly held against a seat 109 in said arm, by a coiled spring 110. A trip-arm or valve-lifter 111 mounted upon the housing 87 is adjustable through the arc in which said ball passes, said arm being fixed as desired, by means of the set screw 112, to lift the ball 108 from its seat, thus opening the passageway 37^a in the feeding arm, to the outer air. A second-ball valve 113 intermittently rests against a seat 114 within the housing 86 to obstruct the air passageway between 120

the grips 40 and pump 39. A rod 115 journaled vertically in the top of said housing 86, has an actuating arm 116 at its upper end and a wedge-shaped lug 117 at the lower end thereof designed to lift the ball 113 from its seat, thus clearing said air passageway. The arm 116 (Fig. 19) is moved backward by the cam surface 118 upon the disc 91 to lift the ball valve 113 and is swung forward by the cam surface 119 also on said disc 91 to release said valve 113, the same being re-seated by gravity and suction.

The delivery arm 38, best seen in Figs. 2 and 4, includes a substantially upright branch 120 and a horizontal branch 121. A boss 122 near the lower end of the former is journaled in a bracket 123 depending from the delivery table 36. An axial passageway in said boss communicates with an air passage way leading through the upper part of the branch 120 and extending into and through the horizontal branch 121 of the delivery arm. A loose sleeve 124 upon said horizontal branch forms a mounting for the suction grip 41. This grip includes a hollow stem 125 slidably longitudinally in an adjustable clamp 126 secured upon said sleeve 124. The forward end of the stem 125 is enlarged to form a suction cup 127 and said stem is connected, by means of a flexible tube 128, with the open end of the branch 121 of said delivery arm. A reciprocating rod 129 connected with actuating mechanism, hereinafter described, is attached to the lower end of the branch 120 and oscillates the arm to carry the suction grip 41 to position for grasping a sheet of paper from the platen and to return said grip to position above the feeding table. In order to clear the platen and to properly seat the suction cup 127 upon a printed sheet, we supply means for tilting the grip during the movement of the delivery arm. An arm 130 carrying a roller 131 is pivoted upon the branch 120 and is connected through a link 132 with an arm 133 on the sleeve 124. This roller 131 rests upon a cam slide 134 and is yieldingly held thereon through the medium of a tension spring 135 arranged between the arm 133 and branch 120. Said cam slide 134 is designed to direct the suction grip so as to clear the platen of the printing press and to properly place said grip upon the printed sheet. A cut-off valve 136, on the bracket 123, is connected through a tube 137 with the intake side of the pump 39 and is also connected through a tube 138 with the hollow boss 122 on the delivery arm. A vertically movable piston 139 in said valve (Fig. 5) is yieldingly depressed by a spring 140, said piston having a port 141 in its side communicating with a passageway 142 leading to the upper end thereof. The port 141 is arranged to register with an opening 143 in said valve,

when the piston 139 is raised against the action of the spring 140, thus clearing the air channel from the pump to the suction grip 41. When said piston 139 is depressed said port 141 is removed from registration with said opening 143 and obstructs the same, thus closing said air channel. A cam 144 having a depression 145 therein is revolvably mounted upon the boss 122 of the delivery arm 38 in such position that the piston 139 rests upon the periphery thereof. This cam has two lugs 146 protruding from its face and extending into the path of the arm 38, one above the boss 122 and the other beneath said boss. These lugs are fixed to the cam 144 in such positions that the upper lug is engaged by the arm 38, when the grip 41 reaches position above the delivery table and the lower lug is engaged by said arm when the grip 41 reaches receiving position upon the platen. The depression 145 in the cam is located with respect to these lugs so that the piston 139 is raised and the valve 136 opened when the grip is in receiving position (dotted lines, Fig. 4) and also during the return of said grip to delivery position (solid lines, Fig. 4).

The combination suction and pressure pump 39, which is of usual construction, is mounted upon a bracket 147 secured to the sub-frame 43. The intake side of said pump is connected with the suction grip 41 on the delivery arm, as above described and is also connected with the suction grips 40 and 40^a on the feeding arm through conduits, heretofore described, which communicate with a tube 148 leading from the intake side of said pump to the hollow standard 44. The driving gear 149 of the pump 39 meshes with an idle gear 150, which is journaled in the sub-frame 43 and driven from the gear 33 of the printing press.

The mechanism employed for actuating the feeding and delivery arms will now be described.

To a shaft 151, mounted between the sub-frame 43 and a support 152, we have fixed three cams 153, 154, and 155 and a driving gear 156 which meshes with a gear 157 formed integrally with the idle gear 150. This gearing is timed so that the cams turn through 360 degrees during a complete revolution of the driving gear 33 of the printing press. Fig. 18 of the drawings show these cams in detail, the cam 153 being illustrated wholly in solid lines, while the concealed portions of the cams 154 and 155 are respectively shown in dotted and broken lines. A bell crank 158 mounted on the sub-frame 43 carries a roller 159 on the arm 160, said roller resting upon the surface of the cam 153. The other arm 161 of said bell crank is pivotally attached to the rod 129 leading to the delivery arm 38 and a compression spring 162 interposed between

said arm 161 and the sub-frame 43 yieldingly holds the roller 159 against said cam 153. Levers 163 and 164 are pivoted upon shaft 165. The lever 163 has a roller 166 which bears upon the cam 154 and is connected with a tension spring 167 attached to the sub-frame, said spring acting to hold the roller 166 against said cam 154. A connecting rod 168 joins the free end of the lever 163 with the arm 96 on the shaft 94 and causes the feeding arm 37 to swing backward and forward from the feeding table 35 to the platen of the printing press and further causes the connecting rod 71, which is also attached to said arm 96 to reciprocate and rock the bell crank 70 heretofore described. The lever 164 is supplied with a roller 169 bearing upon the cam 155, said roller being yieldingly held on the surface of said cam by means of a tension spring 170 arranged between said lever and the sub-frame 43. A connecting rod 171 joins said lever 164 with the disc 91, the connection between said rod and disc being made at a point near the periphery of the latter, whereby the eccentric (cylinder) 89 is oscillated upon the raising and lowering of said lever 164. The cams 153, 154 and 155 are designed to operate the feeding and delivery arms 37 and 38 as shown in Figs. 20 to 29 inclusive. Beginning with Fig. 20, the arm 37 is shown approaching the feeding table 35, which movement is caused by the cam 154. In Fig. 21, the feeding arm 37 has reached its highest point, the cam 154 being formed to hold the shaft 94, temporarily against further rotation. At this point it will be seen that a counter-clockwise rotation of the eccentric 89 is caused by the cam 155. This movement shifts the arm 37 longitudinally toward the feeding table (Fig. 22) then tilts said arm downward (Fig. 23) thus placing the suction grips 40 and 40^a in position against the lower margin of the first sheet upon the feeding table. At this point the cam surface 118 upon the disc 91 swings the arm 116 (dotted lines Fig. 14, solid lines Fig. 19) and lifts the cut-off valve 113, thereby causing suction at the mouths of the grips 40 and 40^a, which grasp the adjacent sheet of paper. Continued rotation of the cam 155 (Fig. 24) turns the eccentric 89 in a clockwise direction, thus tilting the arm 37 upward and sliding the grasped sheet upon the second sheet. This preliminary sliding motion of the first sheet breaks any shreads or the like which may connect the same with other sheets and effects a complete separation of said sheet from the second sheet in case the air jet 42 has so failed to do. At this point the cam 153 operates to advance the delivery arm 38. Continued rotation of the cam 155 (Fig. 25) withdraws the feeding arm 37 through the action of the eccentric

89 and carries the sheet to a position removed from the front guides 84. At this stage the suction grip 41 on the delivery arm 38 grasps the printed sheet from the platen 32 of the press. Upon further rotation of the cams 153, 154 and 155 (Figs. 26 and 27) the cam 154 causes the feeding arm 37 to swing downward with decreasing speed, the cam 155, through the eccentric 89, lowers said arm longitudinally and the cam 153 returns the delivery arm 38. Continuing, (Fig. 28) the cam 154 swings the feeding arm to extreme rearward position, at which point or sooner, according to the adjustment of the trip-arm 111, the ball-valve 108, (Figs. 12 and 13) in the feeding arm 37 is unseated thus discontinuing the suction in the grips 40 and 40^a and releasing the sheet upon the platen 32. Further movement of the cam 155 (Fig. 29) quickly lifts the feeding arm 37 longitudinally through the action of said eccentric, to clear the platen 32, while continued rotation of the cam 154 returns the feeding arm 37 toward the feeding table with increasing speed. Just prior to the unseating of the ball-valve 108, the cam surface 119 on the disc 91 swings the arm 116 (solid lines Fig. 14, dotted lines Fig. 19) thus permitting the ball valve 113 to fall back upon its seat 114, and close the passageway leading to the suction grips on the feeding arm 37.

A yielding finger 172 attached to the lower end of the feeding arm 37 (Fig. 15) extends beneath the tips of the suction grips 40 and 40^a. This finger presses gently down upon a sheet as it approaches position against feed guides 173 upon the platen of the press and insures the proper placement of said sheet against said guides.

The mechanism provided for actuating the tripping lever 34 upon the press, when the grips 40 and 40^a fail to grasp a sheet of paper, includes a piston 174 (Fig. 12) located within the hollow standard 44, beneath the opening 175 leading to the intake side of the pump 39. A stop-pin 176 in said standard limits the downward movement of said piston. Depending from the piston 174 is a chain 177, which is attached at its lower end to a lever 178. Said lever is pivoted near the middle thereof to the sub-frame 43, the forward end of said lever to which said chain is attached, being supplied with a sliding weight 179, while the rear end thereof is connected through a link 180 with an arm 181 upon a rock-shaft 182 mounted on the legs 31^a of the bed 31. Attached to one end of said rock shaft 182 (Fig. 3) is an arm 183 with a pin 184 therein. A bar 185 slidably mounted at its rear end in a guide 186 is pivotally attached at its forward end to the tripping lever 34 of the press. This bar is notched at 187, said notch being arranged to receive the pin 184 in the arm 183 at which

130

time the oscillatory movement of the bed 31 is imparted to the tripping lever 34, thus preventing registration between the bed 31 and platen 32. When, by reason of suction 5 in the grips 40 and 40^a a sheet is grasped from the feeding table, the piston 174 in the standard 44 is drawn upward by suction and operates through the lever 178 and rock-shaft 182 to hold the pin 184 out of the path 10 of the notch 187 in the bar 185. In such case, the neutral position of the tripping-lever 34 is unaltered. If for any reason, a sheet is not grasped by the grips 40 and 40^a at feeding position and the mouths of said 15 grips are unobstructed, no suction is effected in the standard 44 and the piston 174 remains at point of rest upon the stop-pin 176. The action of the weight 179 on the lever 178 in this event causes the pin 184 to enter 20 the notch 187 in the bar 185. Forward movement of the bed then results in shifting the lever 34, thereby preventing contact between the bed and platen. The subsequent grasping of a sheet by the grips 40 and 40^a 25 causes the removal of the pin 184 from engagement with the bar 185, whereby the lever 34 is left in normal position and the bed again permitted to contact with the platen. By throwing the lever 34 by hand 30 out of neutral position, whenever desired, the platen is prevented from contacting with the bed.

We employ a relief valve 188 (Fig. 1) in the connection between the pump 39 and standard 35 44 to automatically admit air thereto when suction in the conduits becomes greater than is required. Referring to Fig. 17, it will be seen that the body 189 of the valve is threaded in the standard 44. A compartment 40 190 within said body communicates with the passageway in said standard and also through an elbow 191, with the tube 148 leading to the pump 39. Air inlet openings 192 in the body 189 of the valve are 45 normally closed by a valve head 193. A valve stem 194 for said head is slidable in the body 189 and carries at its threaded extremity, an adjusting nut 195 and a lock nut 196 therefor. Interposed between the body 50 189 and said adjusting nut 195 is a compression spring 197, the tension of which is regulated by the adjustment of the nut 195. Pressure from without forces the valve head 193 inward, when suction within the conduits becomes excessive. Air then enters the compartment 190 through the openings 192, until the valve head 193 is reseated by the 55 action of the spring 197.

In accordance with the patent statutes we 60 have described the principles of operation of our invention together with the apparatus which we now consider to be the best embodiment thereof, but we desire to have it understood that the construction shown is 65 only illustrative and that the invention can

be carried out by other means and applied to uses other than those above set forth within the scope of the following claims.

Although driven from the press mechanism and coordinated therewith and with each other, the pack advancing means, the sheet feeding means and the sheet delivery means are adapted to be severally swung into inoperative positions, such placement of said means permitting of unhampered 70 access to selected portions of a press or to either of said means with a minimum disturbance of parts. The shifting of the pack advancing means and of the feeding means into inoperative positions, singly or together, 75 is attended with the throwing out of operation of said means without disturbing the action of the delivery means, while the shifting of the delivery means into inoperative 80 position is attended with the throwing out of operation of said means without disturbing the action of the pack advancing and feeding means. In addition, therefore, to having selective access to press parts and to 85 said means, it will be understood that the press may be conveniently operated entirely by hand, partly by hand and partly automatically or entirely automatically as desired. The pack advancing means is rendered 90 inoperative and moved out of the way 95 of an operator by first disconnecting the rod 71 from the pin 72 and then swinging the table back, as shown in dotted lines in Fig. 6. The sheet feeding means is rendered inoperative and placed in position unobstructing 100 hand feeding by swinging the arm 37 upward above its normal sheet receiving position (Fig. 1) and thus holding the same by any suitable means not shown. Prior to elevating said arm 37 the rod 71, 105 just mentioned, is disconnected from the pin 72. In elevated position out of the way of an operator, the spring 167 is extended and the roller 166 on the arm 163 lifted from engagement with the cam 154. The 110 sheet delivery means is rendered inoperative position so as not to obstruct hand delivery, by uncoupling the rod 129 (Figs. 3 and 4) from the stud on the branch 120 and tilting said branch back out of the way. 115 Releasing the feeding arm 37 to the action of the spring 167, permits of return of the roller 166 to engagement with the cam 154 and the swinging of the feeding table back to operative position (solid lines, Fig. 6) 120 accompanied by the coupling of the rod 71 with the bell crank 70 replaces the feeding and pack advancing means in timely operation. The re-coupling of the rod 129 with the branch 120 results in restoring the sheet 125 delivery means to timely operation.

While we have shown a platen press in connection with our improved device and have stated that the preferred use of said device is found in combination with such 130

presses, it has been proven to be well adapted for use with cylinder presses. We, therefore, desire it to be expressly understood that we do not limit the use of our improvement to platen presses, but claim protection covering it in connection with any printing couple or analogous device.

Having described our invention what we claim as new and desire to protect by Letters 10 Patent is:

1. The combination with a printing couple of a sheet support, an eccentric, an oscillating feeding arm carried by said eccentric, a grip on the feeding arm, said arm being 15 adapted to take a sheet from the support, deliver it in receiving position to a member of the printing couple and return to starting position, and means for rocking the eccentric to extend the arm at both extremities 20 of its throw and to retract the same at the beginning of its swing therefrom.

2. The combination with a printing couple of a sheet support, an eccentric an oscillating feeding arm carried by said eccentric, a grip on the feeding arm, said arm being 25 adapted to take a sheet from the support, deliver it in receiving position to a member of the printing couple and return to starting position, means for rocking the eccentric to 30 affect the extension and retraction of said arm in its swing and to correct the location of said eccentric prior to subsequent actuations of said arm by said eccentric.

3. In a sheet feeding device adapted to 35 take sheets from a sheet support and present them to a member of a printing couple, an oscillating tubular feeding arm swung from a support above the printing couple, a source of air exhaust connected with the 40 head end of said arm, a pneumatic grip on the lower end of said arm, said arm in its cycle of operation being arranged to swing said grip from a position of engagement with a sheet on said support to a position 45 of placing said sheet on said member of the printing couple, an air ingress duct at the head end of said arm, a valve closing said duct, and adjustable means for opening said valve to release the sheet 50 grasped by the grip at a predetermined position on said member of the printing couple.

4. The combination with a printing couple of a sheet support forming a rest for the 55 lower edges of a pack of sheets, a front guide for said sheets at the forward margin of said support, a rocking eccentric above the printing couple, an oscillating feeding arm carried by said eccentric, a grip on the feeding arm, said arm in its cycle of operation 60 being adapted to take a sheet from the sheet support, deliver it in receiving position to a member of the printing couple and return to starting position, the operation of the arm including longitudinal movements with 65 swinging movements to separate the sheet

from the pack, to clear the support, to clear the sheet when deposited and to return the grip to position in proper relation to the support.

5. The combination with a printing couple 70 and support for a pack of sheets, of a feeding device adapted to take sheets, one at a time, from the pack, carry them edge foremost to the sheet receiving member of the printing couple and release said sheets, during edgewise movement, closely above said couple member, said device comprising a grip, a mounting therefor and means for shifting the mounting to carry the grip forward to said couple and back to the sheet 80 support, said mounting being adapted to carry said grip in its return throw to a point beyond sheet grasping position to effect a sliding, stripping movement of the grasped sheet on the adjacent sheet prior 85 to the forward throw of the grip.

6. In a sheet feeding device adapted to 90 take sheets from a sheet support and present them to the platen of a printing couple, an oscillating feeding arm swung from a support above the bed, a pneumatic grip thereon, said arm in its cycle of operation being arranged to swing the grip from a position first engaging a sheet on said support, thence 95 upwardly substantially parallel with the plane of the surface of said sheet to disengage said sheet from said support, thence outwardly away from said sheet support and thence downwardly to a position of delivery to said platen and means for oscillating said arm.

7. The combination with a printing couple 105 of a sheet support, an oscillatory feeding arm adapted to take sheets from said support and present them to a member of the printing couple, grips on said arm, an eccentric upon which said arm is mounted, means for swinging said arm and means for turning said eccentric to vary the reach of the arm.

8. The combination with a printing couple 115 of a sheet support, a feeding arm above the printing couple, said arm being adapted to take sheets from said support and present them in receiving position to one member of the printing couple, a suction grip on said arm, a rocking eccentric upon which the arm oscillates, a source of suction communicating with said grip through said eccentric and arm and means for intermittently cutting off the suction in said grips.

9. The combination with a printing press, an oscillatory feeding arm swung from an overhead support and adapted to take sheets from a sheet support having a front guide 125 and present them to the platen of said press, a pneumatic suction grip on said arm, means for swinging the arm between receiving and discharging positions, an eccentric upon which said feeding arm is mounted and 130

- means for turning said eccentric to supplement the action of the means for swinging said arm, whereby the suction grip thereon is directed to clear the sheet support and 5 platen and also to slide the first sheet engaged upon the second sheet, then carry said first sheet beyond said guide, preparatory to the downward swing of said feeding arm.
10. The combination with a printing press 10 of an oscillatory feeding arm having a bore therein, said arm being swung from a support above the press and adapted to take sheets from a sheet support and present them to one of the press members, a suction 15 grip on said arm, means for swinging the arm and directing said grip to receiving and discharging positions, a source of suction communicating with said grip through the bore in said arm, a spring pressed valve in 20 said bore and an adjustable valve lifter in the path of said valve adapted to lift the valve and open said bore to the outer air, thus discontinuing the suction in said grips and releasing a sheet grasped thereby.
- 25 11. In a sheet feeding device, the combination with a printing couple, a sheet support, an oscillating arm, a suction grip thereon, means for swinging the arm, said grip being adapted to travel in an arc-like 30 path and to take sheets, one at a time, from the support, carry them edge foremost and release the same, during edgewise movement, upon the sheet receiving member of the printing couple, the movement of a sheet 35 by said grip being at a speed sufficiently great to float the trailing side thereof and suction interrupting means adapted to discontinue suction within the grip at different points near the end of its feeding throw to vary 40 the positions of discharge of said sheets.
12. The combination with a printing couple of a pack support, a rocking eccentric above the printing couple, an oscillating feeding arm carried by said eccentric, 45 a grip on the feeding arm, said arm in its cycle of movement being adapted to separate a sheet from the pack on the sheet support, deliver it in receiving position to a member of the printing couple and return 50 to starting position, the movement of the eccentric during the swing of said arm being caused at predetermined times with respect to the position of the arm to properly direct said grip.
- 55 13. In a sheet feeding device, the combination with a printing couple, a feeding arm, a suction grip thereon, said arm being arranged to cause the grip to take sheets from a sheet support and drop them, during 60 edgewise movement, onto the sheet receiving member of the printing couple, means for moving the arm and adjustable suction interrupting means adapted to discontinue suction within the grip at various points in 65 the throw of said arm.
14. In a sheet feeding device adapted to take sheets from a sheet support and present them to a printing press member, an oscillatory arm swung from a support over the press, a pneumatic grip on the lower end 70 of said arm and means for swinging said arm, said arm being arranged to swing said grip with decreasing speed direct from said support to said press member.
15. In a sheet feeding device adapted to 75 take sheets from a sheet support and present them to a printing press member, an oscillatory arm swung from a support over the press, a pneumatic grip on the lower end 80 of said arm and means for swinging said arm, said arm being arranged to swing said grip with varying speed direct from said support to said press member.
16. In a sheet feeding device adapted to 85 take sheets from a sheet support and present them to a printing press member, an oscillatory arm, a pneumatic grip on said arm and eccentric means for swinging said arm with decreasing speed direct from said support to said press member.
17. In a sheet feeding device adapted to 90 take sheets from a sheet support and present them to a printing press member, an oscillatory arm, a pneumatic grip on said arm and eccentric means for swinging said 95 arm with decreasing speed direct from said support to said press member and back to said support with increased speed.
18. In a sheet feeding device adapted to 100 take sheets from a sheet support and present them to a printing press member, an oscillatory arm swung from a support over the press, a pneumatic grip on the lower end 105 of said arm and means for swinging said arm downwardly from said support to said press member and back to said support with a quick start, slow delivery to said member and quick return.
19. In a sheet feeding device adapted to 110 take sheets from a sheet support and present them to the platen of a printing press, an oscillating arm swung from a support over the press, a pneumatic grip on the lower end 115 of said arm and means for swinging said arm, said arm being arranged to swing said grip in a downward arc from said support direct to said platen and back in a different arc beginning above the sheet depositing plane to clear said platen during 120 the tipping operation of the latter.
20. In a sheet feeding device adapted to 125 take sheets from a sheet support and present them to the platen of a printing press, an oscillating arm swung from a support over the press, a pneumatic grip on the lower end 130 of said arm and means for swinging said arm and first raising said grip to slide a sheet from the support upwardly, thence moving said grip outwardly and swinging the grip quickly downwardly with slacken-

- ing speed near delivery to said platen and finally quickly returning said grip to point of beginning adjoining said sheet support.
21. In a sheet feeding device adapted to take sheets from a sheet support and present them to a press member, an oscillatory arm swung from a support over the press, a pneumatic grip on the lower end of said arm and means for swinging said arm 10 downwardly from said support to said member and back to said support with a quick start, slow delivery to said member and quick return.
22. In a sheet feeding device adapted to take sheets from a sheet support and present them in receiving position to a member of a printing couple, an oscillating arm, a grip thereon and yielding means for swinging said arm, said means being adapted to adjust itself to accord with the movement of the arm to and from elevated inoperative position, wherein the members of the printing couple are unobstructed by said arm.
23. In a sheet feeding device, the combination with a printing press, of a feeding table, a feeding arm swung from an overhead support, a suction grip on the arm, means for swinging the arm back and forth in a limited operative cycle of movement, said grip in the operative cycle of said arm being adapted to carry sheets in a downward arc-like throw from the feeding table and drop them during edgewise movement onto the sheet receiving member of the press, said arm having a supplementary upward throw in continuation of its operative upward movement to allow the shifting of said arm into elevated inoperative position unobstructing a make ready attendant, said means for swinging said arm in its operative oscillatory path permitting of the shifting of said arm into inoperative position above its operative path.
24. The combination with a printing press of means for advancing a pack of sheets to be fed, feeding means adapted to take sheets from the pack advancer and present them in receiving position to a printing member of the press and delivery means for removing printed sheets from the press, said means being driven from the press mechanism and co-ordinated therewith and with each other, and said means being severally movable into inoperative positions, the shifting of the pack advancing means and of the feeding means into inoperative positions, singly or together being attended with the throwing out of operation of said means without disturbing the action of the delivery means, the shifting of the delivery means into inoperative position being attended with the throwing out of operation of said means without disturbing the action of the pack advancing and sheet feeding means, whereby ready access may be had to selected portions of the press or to either of said means with the minimum disturbance of parts and whereby the press may be conveniently operated entirely by hand, partly by hand and partly automatically or entirely automatically, as desired.
25. In a sheet feeding device adapted to take sheets from a support and present them to a member of a printing couple, an oscillating arm swung from a point over the printing couple, a grip on said arm and means for swinging the arm, said arm being arranged to carry the grip downward in an arc-like sweep from sheet receiving position adjacent said support to sheet discharging position adjacent to the receiving member of the couple and back again, the return sweep being in a different arc-like path beginning at a point above sheet discharging position.
26. In a sheet feeding device adapted to take sheets from a support above the rear edge of the platen of a press and carry them, lower edge foremost, to varying positions of discharge adjacent to said platen, an oscillating arm swung from a point over the platen, a grip on said arm, and means for swinging the arm to carry the grip in an arc-like path, between said support and platen, said grip being adapted to carry sheets without the aid of any other agency and at a speed sufficiently great to prevent them from settling substantially, by gravity, prior to reaching selected position of discharge.
27. In a sheet feeding device for printing presses, a feeding arm, a suction grip thereon, said arm having a conduit and adapted to take sheets from a sheet support, carry them edge foremost to the sheet receiving member of the press and release said sheets near and at the end of the feeding stroke of said arm, means for moving the arm to direct the grip to and from a position for receiving sheets, a valve in said conduit and means for opening said valve and thereby releasing the sheets in various positions of said arm to accord with the desired positions of rest of said sheets upon the sheet receiving member.
28. In a sheet feeding device, the combination with a printing couple, a feeding arm, a suction grip thereon, said arm being mounted above the printing couple and arranged to cause the grip to take sheets from a sheet support and drop them, during edgewise movement, onto the sheet receiving member of the printing couple, means for moving the arm and suction interrupting means adapted to discontinue suction within the grip at various points near and at the end of its forward stroke.
29. In a sheet feeding device, the combination with a printing couple, of a feeding arm, a suction grip thereon, said arm

- being mounted above the printing couple and arranged to cause the grip to take sheets from a sheet support and carry them edge foremost to the sheet receiving member of the press, means for moving the arm and suction interrupting means adapted to discontinue suction within the grip at various points near the end of the feeding stroke of said arm, whereby ultimate positions of rest of said sheets on the sheet receiving member may be regulated to accord with the speed of operation and character of the stock employed. 65
30. The combination with a printing couple of a sheet support, an oscillating feeding arm having a floating mounting therefor, a grip on the feeding arm, said arm being adapted to take a sheet from the support, swing it to a member of the printing couple and return to starting position and means for actuating said mounting to first extend and then retract said arm to permit the grasping of a sheet on the support and the subsequent clearing of said support by 70 said grip. 80
31. The combination with a printing couple of a sheet support, an oscillating feeding arm having a floating mounting therefor, a grip on the feeding arm, said arm being adapted to take a sheet from the support, swing it to a member of the printing couple and return to starting position and means for actuating said mounting to extend and later retract said arm to permit 85 the deposit of the sheet in close proximity to said member of the printing couple and to prevent subsequent interference of the grip with the deposited sheet. 90
32. The combination with a printing couple of a sheet support, an oscillatory feeding arm adapted to take a sheet from the support, present it in sheet receiving position to a member of the printing couple and return to starting position, said arm being first extended then retracted at the ends of its throws to reach a sheet on the support and thereafter clear said support and to accurately deposit the sheet and thereafter clear the sheet deposited. 95
33. In a sheet feeding device for printing presses, a feeding arm, a suction grip thereon, a suction pump, a suction passageway communicating with said grip, said arm being adapted to take sheets from a sheet support, carry them to the sheet receiving member of a press and release said sheets near the end of the feeding stroke of said arm, means between said pump and grip for obstructing said passageway prior to the completion of the feeding stroke of said arm, a valve to admit air to the passageway between said grip and said obstructing means and means for actuating said valve to 100 release sheets in various positions of said arm near the end of the feeding stroke thereof. 105
34. In a sheet feeding device adapted to take sheets, on edge, from a support above the platen of a press and carry them, edge foremost, to said platen and also take sheets, edge foremost, from the platen, a feeding arm, a grip thereon, said arm being adapted to swing said grip upward and downward between the support and platen, a delivery arm, a grip thereon, said delivery arm being adapted to carry said grip forward to and backward from the platen, beneath the said support, the movements of said arms being co-ordinated to avoid interference with the platen and with each other. 110
35. The combination with a printing press, an oscillatory feeding device adapted to take sheets from a sheet support and present them to a member of said press, said device including an arm, a pneumatic suction grip on said arm, means for swinging the arm between receiving and discharging positions, an eccentric upon which said feeding arm is mounted and means for turning said eccentric to supplement the action of the means for swinging said arm, whereby the suction grip is directed to reach a sheet on the sheet support, then clear said support preparatory to the sheet carrying throw of said arm. 115
36. The combination with a printing couple, a sheet support, a grip adapted to take a sheet from the support, swing it edge foremost to a member of the printing couple and return to starting position, a mounting for the grip, means for moving said mounting to swing the grip and additional means for further actuating said mounting to permit the depositing of a sheet by said grip in close proximity to said member of the printing couple and to avoid subsequent interference of the grip with the deposited sheet. 120
37. The combination with a printing couple, of a sheet support, a grip adapted to take a sheet from the support, swing it edge foremost to a member of the printing couple and return to starting position, a mounting for the grip, means for moving said mounting to swing the grip and additional means for further actuating said mounting to cause the grip to reach beyond its swinging path for a sheet on the sheet support then clear said support preparatory to the sheet carrying throw of said grip by 125 said swinging means. 130
- In testimony whereof, we have signed our names to this specification.
